United States Patent Office

Des. 217,984
Patented July 7, 1970

217,984

DECORATOR PANEL

Daniel M. Pearl, Skokie, Ill., assignor, by mesne assignments, to Bolen International, Inc., Niles, Ill., a corporation of Illinois

Filed Jan. 27, 1969, Ser. No. 15,519

Term of patent 14 years

Int. Cl. D25—01

U.S. Cl. D54—2

Fig. 1.

Fig. 4.

FIG. 1 is a front elevation of a decorator panel of this invention, showing in phantom a second decorator panel, both of which panels are supported by standards, also shown in phantom;

FIG. 2 is an enlarged front elevation of a portion of the decorator panel of FIG. 1;

FIG. 3 is a view taken substantially along line 3-3 of FIG. 2; and

FIG. 4 is an enlarged portion of FIGS. 1 and 2 showing the wrought iron surface effect incorporated throughout the surface of the decorator panel of FIG. 1.

The dotted lines of FIG. 1 are disclosed for illustrative purposes only and form no part of the claim.

I claim:

The ornamental design for a decorator panel, substantially as shown and described.
